A. P. STRONG

GRATE LINK

Filed Jan. 24, 1923

Inventor
Arthur P. Strong
By August C. Evans, Atty.

UNITED STATES PATENT OFFICE.

ARTHUR P. STRONG, OF CHICAGO, ILLINOIS.

GRATE LINK.

Application filed January 24, 1923. Serial No. 614,516.

This invention relates to links for furnace grates and more particularly traveling chain grates.

The main object of my invention is to provide the links with overlapping side flanges to prevent droppage sifting through the grate yet allow draft to pass through the same to sustain the fire thereon.

A further object of my invention is to have these flanges so arranged that they may have movement relatively to each other to discharge the droppage therefrom as the links follow around one end of the grate.

The invention consists further in the matters hereinafter described and more particularly set forth in the appended claims.

In the accompanying drawings—

Fig. 1 is a vertical longitudinal sectional view taken through the rear or tail end of an endless chain grate made of links of my invention;

Fig. 2 is an enlarged side elevational view of a number of said links arranged as in said grate;

Fig. 3 is a bottom plan view of the links in Fig. 2;

Fig. 4 is a transverse vertical sectional view taken on line 4—4 of Fig. 2; and

Fig. 5 is an end view taken of a link.

The links of my invention are indicated by 1 and all are alike so that a description of one will suffice for all. Each link 1 has a main body portion or web 2 laterally narrow and extending from end to end of the link.

The web 2 is upright when the link is in a grate structure. The upper end of the web 2 terminates in a larger or head portion 3, which is the fuel supporting part of the link when in the grate structure. This head portion 3 extends the full length of the link and projects outward on opposite sides of said web 2, as shown in Fig. 4.

Below the head portion 3, the web 2 is provided on each side with outwardly projecting flanges 4, 5, 6, 7. These flanges, on each side of the link, are arranged with the flanges 4 and 7 inclined downward and inward toward each other and at opposite ends of the link, while the flanges 5 and 6 are between them. The latter meet at their upper ends and diverge downward toward the associated end flanges 4 and 7, respectively, as shown in Fig. 2.

The end flanges 4 and 7 and their associated mid-flanges 5 and 6, on each side of the

link, terminate in circular bosses 8, 9, which define cylindric holes or bores 10, 11 through the web 2 adjacent the ends thereof. These bores are made to accommodate link supporting rods 12, 12 of the grate structure. The lower edges of the webs 2 at the front and rear ends of the links are shaped to follow around the bosses 8, 9 and thus provide spaces for the teeth of the sprocket wheels used to drive the grate.

When assembled to provide the grate structure shown in Fig. 1, the links 1 are arranged in rows extending lengthwise of said structure. The links in each row are in endwise alignment and each link is mounted on two rods 12, 12, as shown in Fig. 3. The links in adjacent rows are in staggered relation, so that break joints are provided at the ends of the links, as shown in Fig. 3. This makes the rods 12 at the front and rear ends of a link in one row support the rear and front ends, respectively, of the links in the adjacent rows on opposite sides thereof.

The flanges 5 and 6 of each link are in line, with the centers of the adjacent bores 10, 11, as indicated by the dotted lines *a*, *b* in Fig. 2. The end flanges 4 and 7 of each link are offset above these centers, as shown by dotted lines *c*, *d* in said figure. By the staggered relation of the links, the end flanges 4 and 7 of one link are adjacent the mid-flanges 5 and 6, respectively, of the links on opposite sides thereof, and by the offsetting mentioned, these end flanges are above the mid-flanges, as shown in Fig. 4. As there illustrated, the said flanges 5 and 6 extend outward from the webs 2 a greater distance than the end flanges 4 and 7, with the result that the latter are overlapped by the former and prevent droppage sifting through the grate. Said flanges catch droppage after passing between the heads 3, 3 and, by moving relatively to each other as the links turn over the tail end of the grate, dump or discharge the droppage over such end of the grate. These flanges being offset or spaced above each other in the manner described, allow draft to pass upward through the grate through the spaces between said flanges. The end flanges 4 and 7 are required to pass the associated heads 3 as the links turn around the ends of the grate. To allow this, said flanges project outward from the webs 2 just far enough to clear said heads.

When in chain grate form with upper and lower leads or runs, as shown in Fig. 1, these links 1, 1 prevent droppage sifting through the upper lead onto the lower lead. 5 This avoids the use of droppage collecting means or floors associated with the lower leads, as heretofore. Thus, with the droppage collecting means embodied in the links themselves, separate and additional expensive means for this purpose, as heretofore used, is avoided, with the attendant saving in material, structure and cost of operation.

While I have shown and described in detail links constructed and arranged in accordance with my invention, it is of course to be understood that the details of construction and arrangement of parts may be variously changed and modified without departing from the spirit and scope of my 20 invention.

I claim as my invention:

1. In an endless chain grate, a plurality of connected links having vertical webs and arranged in parallel rows with the webs laterally spaced apart, each link having outwardly projecting inclined mid and end flanges on opposite sides of its web and disposed below the fuel supporting portion thereof, certain flanges of the links of alternate rows projecting over flanges of the links of intermediate rows to prevent fuel sifting through the grate and being vertically spaced for the passage of draft between them, said links each having rod receiving openings between the mid and end flanges thereof.

2. A grate link of the character described, comprising a web having an enlarged upper edge forming a head, inclined mid and end flanges projecting outward from a side of said web below said head, said mid flanges projecting outward farther than said end

flanges, and said web having rod receiving openings therein.

3. In an endless chain grate, a plurality 45 of connected links arranged in rows lengthwise of said grate, said links having vertical webs with enlarged heads laterally spaced apart for draft purposes, said webs having outwardly projecting inclined end and mid 50 flanges on opposite sides thereof and overlapping in the spaces between the links below the heads to prevent droppage sifting through the grate, said links having holes therein and provided with outwardly projecting tubular bosses around the same, and rods extending through said holes for connecting the links, said bosses being between the end and mid flanges with the adjacent ends of said flanges terminating in said 60 bosses, the links in one row being staggered with respect to the links in the rows on opposite sides thereof and arranged with the end flanges above the mid flanges on links 65 of adjacent rows.

4. A grate link of the character described, comprising a web having an enlarged upper edge forming a head, inclined end and mid flanges on opposite sides of said web below said head with the mid-flanges projecting 70 outward farther than said end flanges, said web having two holes therein between the adjacent ends of said end and mid-flanges, tubular bosses on said webs and surrounding said holes with the end and mid-flanges 75 terminating therein, said flanges being so disposed that extensions of the end flanges would pass above the centers of said holes and extensions of the mid-flanges would pass through said centers.

In testimony that I claim the foregoing as my invention, I affix my signature, this 20th day of January, A. D. 1923.

ARTHUR P. STRONG.
